UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

GUN.

1,323,640.

Specification of Letters Patent.

Patented Dec. 2, 1919.

Application filed May 17, 1919. Serial No. 297,898.

To all whom it may concern:

Be it known that I, CHARLES F. LEFEVER, a citizen of the United States of America, residing at Plymouth, in the county of 5 Wayne and State of Michigan, have invented certain new and useful Improvements in Guns, of which the following is a specification, reference being had therein to the accompanying drawings.

10 The invention relates to spring air guns of that type in which the spring is compressed by the movement of a handle slidable upon the barrel, or what is commonly known as a pump action.

15 It is the object of the invention to obtain an easily operated mechanism, to simplify the construction of parts and to secure various advantages as hereinafter more fully set forth.

20 In the drawings:

Figure 1 is a side elevation of the gun;

Fig. 2 is a vertical longitudinal section through a portion of the barrel showing the operating mechanism;

25 Figs. 3 and 4 are similar views showing the operation of charging or compressing the spring;

Fig. 5 is a cross-section on line 5—5

Fig. 3;

30 Fig. 6 is a cross-section on line 6—6 Fig. 3;

Fig. 7 is a sectional elevation showing the handle of the pump actuating mechanism in its relation to the barrel;

35 Fig. 8 is a perspective view of the handle detached and link actuated thereby detached;

Fig. 9 is a cross-section on line 9—9

Fig. 7;

40 Fig. 10 is a cross-section on line 10—10 Fig. 7;

Fig. 11 is a cross-section similar to Fig. 10 slightly modified;

45 Figs. 12 and 13 are perspective views of a portion of the frame and the trigger guard to be attached thereto.

In the present state of the art various constructions of pump operating mechanisms for spring air guns have been devised, in 50 some of which the operation of the actuating handle moves the plunger to compress the spring against a stationary abutment, while in others the actuating mechanism moves the spring abutment to compress the spring against the plunger.

One of the features of the present invention is a mechanism in which the plunger and spring abutment are simultaneously actuated in opposite directions. This has the advantage that the mechanism can be 60 condensed, for each end of the spring is moved only one-half the distance. A further advantage of the construction is that the mechanism may be actuated with less labor, due to the fact that at the completion 65 of the movement when the spring is under strongest tension the leverage is most favorable for increasing power.

In detail, A is the false barrel of the gun containing the usual true barrel B. C is the stock and D is the frame for uniting the barrel and stock. This frame is preferably formed up of sheet metal with a segmental cylindrical portion D' telescopically engaging the barrel and having depending parallel spaced flanged portions D². The segmental cylindrical portion is more than a half circle in cross-section and forms a guideway for the slidable compression chamber E and slidable spring abutment F. 80

The compression chamber E is a cylinder fitting within the segmental portion of the frame and having at its forward end an abutment G preferably cup-shaped and filled with packing material G'. This abutment normally rests above a stationary abutment H which is secured within the false barrel and the packing material seals the joint so as to prevent leakage of air. Within the chamber E is a slidable piston I which is provided with a shank I' extending rearwardly therefrom and preferably tubular and of sufficient size to form a guide for a spring J. This spring is confined within the annular space between the shank I' and the compression chamber E, its forward end bearing against the piston I while its rear end normally extends beyond the compression chamber and into engagement with the slidable abutment F. This abutment is preferably formed of pressed sheet metal and in addition to forming a seat for the spring has mounted thereon the sear K. As specifically shown, the abutment has a segmental cylindrical portion F' for fitting within the 105 corresponding portion of the frame and has also the spaced parallel flanged portions F² which fit within the parallel flanges D².

The sear is mounted on a pivot pin K' passing transversely through the abutment mem- 110

ber and has the forward extension carrying the detent K^2 for engaging a coöperating detent I^2 on the plunger shank I' . The sear is further provided with a rearwardly extending arm K^3 which in the normal position of parts, as shown in Figs. 2 and 4, is arranged above the trigger L so that when the latter is pulled an arm L' thereof will raise the arm K^3 to release the sear. For holding the sear from accidental release a spring M is placed to pass downward upon the arm K^3 and an abutment for this spring is formed by a rearward extension F^3 of the abutment F . This rearward extension also forms a safety device which, as will be hereinafter described, forces the trigger out of the path of the sear when the latter is returned to operative position.

The pump actuating mechanism comprises a handle member O slideable longitudinally of the barrel and a toggle lever connection comprising the link P and the lever Q . The link P is preferably formed from sheet metal, being of a U -shaped cross-section and tapering from its rear to its forward end so as to make a continuous line from the handle to the bottom of the frame D . The lever Q is normally concealed within the flanges D^2 of the frame and engages a fulcrum pin Q' which passes transversely therethrough and through the flanges D^2 . On opposite sides of this fulcrum the lever Q is pivotally connected respectively to the links R and S , the former extending within the slideable abutment F and engaging the pivot pin K' , while the latter extends forward within the frame and is attached to a depending flange E' on the compression chamber E . Thus when the lever Q is moved angularly about its pivot Q' the link R will move the abutment F in one direction while the link S will move the compression chamber E in the opposite direction. The arrangement of the parts is also such that in the initial movement when the spring is under light tension the leverage is least favorable for power, while during the subsequent movement of the lever the power is increased so as to overcome the increasing resistance of the spring. Thus, as shown in Fig. 3, where the spring is fully compressed and the detents on the plunger shank and sear are in engagement, the lever Q is substantially at right angles to the axis of the barrel and exerts its greatest power upon the links R and S . Also the toggle formed by the link P stands substantially perpendicular to the lever Q and is exerting its greatest power in the movement of said lever under the actuation of the slideable handle O .

The actuating handle O must be guided to move longitudinally of the barrel and secured against detachment therefrom. This I have accomplished by forming the handle

with a concave segment O' for fitting about the barrel and providing segmental metal flanges T fitting the interior of said barrel. The flanges T are connected to the handle O by a shank passing through the seam in 70 the false barrel and preferably this shank and the flanges are formed of a single sheet metal blank folded to form a tubular portion T^2 for engaging a central longitudinal bore in the handle. The shank T' passes 75 through a slit or saw kerf in the handle and thus the one member forms a tie connection and a guide for the handle on the barrel. I also preferably provide a metal bearing for 80 engaging the outside of the barrel, this being formed by segmental flanges T^3 on the shank T' and spaced from the flanges T equal to the thickness of the barrel. As a modification of the construction just described and as shown in Fig. 11, segmental 85 flanges U may be struck outward from the false barrel to engage the flanges T . The rear end of the portion T^2 is pivotally attached to the link P by a pin P' , and said link is pivotally attached to the lever Q by 90 a pin P'' .

With the construction as thus far described, in operation the parts are normally in the position, as shown in Fig. 2, where the abutment G of the compression chamber F is bearing against the abutment H in the false barrel. The member F is also in its rearmost position where the sear K is arranged with its actuating arm K^3 above the arm L' of the trigger L . The link P and lever Q are in substantial alinement with each other and the handle O is in its farthest advanced position on the barrel. To load the gun the handle O is slid rearwardly and as the point of pivotal connection P^2 between the link P and lever Q is below the common plane of the fulcrum Q' and pivot P' , said link and lever will break downward. The continued rearward movement of the handle will increase the angular 105 relation between the link P and lever Q , thereby increasing the power of the movement until, as shown in Fig. 3, they stand at substantially right angles to each other. The swinging movement of the lever Q will 110 first actuate the abutment F through the connecting link R and pivot pin K' . A slight degree of lost motion is preferably provided between the link S and the lever Q by forming a slotted bearing S' for engaging the connecting pivot pin S^2 . Thus during the interval when this lost motion is taken up the lever is actuating only the slideable abutment F . When, however, the link S is also actuated this will draw rearward 115 the compression chamber E and in so doing will compress the spring J between the piston I and the abutment F until the sear passes over the tapered head I^3 of the shank I' and engages the detents K^2 and I^2 . 120 125 130

The handle O is then moved forward to return the link P and lever Q to their original positions. This will also return the abutment F and the compression chamber E, but 5 inasmuch as the sear is in engagement with the shank I' the piston I is held from forward movement and is compelled to move rearwardly with the abutment F. This will 10 separate the piston I from the abutment G and will fill the space therebetween with air which is to be subsequently compressed. The piston I is provided with the usual tubular forwardly extending member V which 15 telescopically engages the true barrel B and the air for filling the compression chamber enters through this tube and through a small port V' therein opening into the chamber.

The operation just described has compressed the spring and moved the piston 20 rearward in the compression chamber into position ready for firing. The movement has also brought the sear into operative relation to the trigger, but accidental release has been prevented by the rearward extension 25 F³ of the abutment member F which presses the arm L of the trigger downward in advance of the detent. At the completion of the movement the member F³ passes out 30 of engagement with the trigger so that the latter can be pulled, whereupon the arm K³ will be raised, the sear disengaged from 35 the shank I' and the spring released to propel the piston forward. This compresses air outward through the port V' and tube V into the true barrel where it ejects the projectile.

The elements of the mechanism above described are formed to a great extent from 40 sheet metal stampings which reduces the cost of manufacture and also standardizing the parts so that they may be used interchangeably in different guns.

One novel detail of construction is the 45 trigger guard, shown in Figs. 12 and 13, in which W is a U-shaped strap bent up from sheet metal and having projecting laterally from one of the legs of the U the apertured ears W', while the opposite leg is 50 provided with the notches W² on opposite sides thereof. The frame D is formed with inturned flanges D³ on the lower side thereof in rear of the down-turned flanges D² and these inturned flanges are cut away at 55 D⁴ for the passage of the trigger. In rear of this cut away portion are the stop portions D⁵ and the notches W² in the leg of the trigger guard engage the flanges D³ adjacent to the stops D⁵. Also the apertured 60 ears W' pass between the flanges D², while the leg of the U from which they extend forms a closure at the end of said flanges. Thus the guard is complementary to the frame and may be easily engaged therewith, 65 being secured by a screw W³ passing

through the apertured ears W' and the flanges D².

What I claim as my invention is:—

1. In an air gun, the combination with a frame, of an air compression cylinder having an abutment at the forward end thereof, a piston in said cylinder, a shank extending rearwardly from said piston, a spring bearing against said piston and an abutment for the opposite end of said spring, means 70 for simultaneously actuating said compression cylinder and spring abutment in opposite directions to compress the spring, and a sear mounted on the spring abutment for engaging with said piston shank to retain 75 the spring compressed.

2. In an air gun, the combination with a frame, of an air compression cylinder having an abutment at its forward end slidable in said frame, a piston within said cylinder, 80 a shank extending rearwardly from said piston, a spring sleeved on said shank and extending into said cylinder against said piston, an abutment for the opposite end of said spring slidable in said frame, a lever 85 mechanism for simultaneously actuating said compression cylinder and spring abutment in opposite directions, and a sear carried by said abutment for engaging the piston shank when the spring is compressed 90 and for drawing the piston outward in the cylinder when said cylinder and abutment are restored to normal position.

3. In a spring air gun, the combination with a frame having a segmental cylindrical portion and parallel flanges depending therefrom, of an air compression cylinder slidable in the cylindrical portion of said frame and having a spring abutment at its forward end, a piston within said cylinder, 100 a piston shank extending rearward therefrom, a spring sleeved on said shank extending into said cylinder against said piston, an abutment for the rear end of said spring slidable in the cylindrical portion of said frame, a sear mounted on said abutment, a lever arranged between the flanged portion of said frame, and links arranged on opposite sides of the fulcrum of said lever connected respectively to said cylinder and 105 spring abutment for actuating the same simultaneously in opposite directions, whereby the spring is compressed and the sear engaged with the piston shank when said lever is moved in one direction and the cylinder and spring abutment are restored to 110 normal position when the lever is moved in the opposite direction, and a trigger arranged in operative relation to the sear when the latter is in normal position.

4. In a spring air gun, the combination with a frame having a cylindrical portion and spaced parallel flanges depending therefrom, of a barrel extending forward and in alinement with the cylindrical por- 115 120 125 130

- tion of said frame, and a stationary abutment adjacent to the junction between the barrel and the frame, an air compression cylinder slideable in said frame and having an abutment at its forward end for bearing against said stationary abutment, a piston in said cylinder, a piston shank extending rearwardly therefrom, a spring sleeved upon said shank extending into said cylinder
10. against piston, an abutment for the opposite end of said spring slideable in said frame, a sear carried by said abutment, a lever between the parallel flanges of said frame, links connected to said lever on opposite
15. sides of the fulcrum thereof and respectively connected to said cylinder and spring abutment, a pump handle slideable longitudinally of said barrel, and a link connecting said handle with said lever.
20. 5. In a spring air gun, combination with a frame, of an air compression cylinder slideable within said frame and having an abutment at the forward end thereof, a piston within said cylinder, a shank extending
25. rearward from said piston, a spring sleeved upon said shank extending into said cylinder against said piston, an abutment for the rear end of said spring slideable within said frame, a sear carried by said abutment and
30. a lever fulcrumed within said frame and normally lying substantially parallel to the axis of said cylinder with portions on opposite sides of the fulcrum at a slight angle to said axis, and links connected to said portions on opposite sides of the fulcrum and respectively connected to said cylinder and abutment, whereby in the swinging of said lever said cylinder and spring abutment are actuated in opposite directions with increasing
35. power of leverage until the spring is fully compressed and the piston shank engaged with the sear.
40. 6. In a spring air gun, the combination with a frame, an air compression cylinder, a piston therein, a shank extending rearward from said piston, a spring sleeved on said shank, an abutment for the rear end of said spring slideable within said frame, a sear carried by said abutment, a lever for
45. actuating said abutment and sear in a forward direction to compress the spring and engage said shank with said sear, to then return said abutment, sear, shank and piston, a trigger in operative relation to said
50. sear when in normal position, and safety means on said spring abutment for forcing said trigger out of the path of said sear when the latter is being returned to normal position.
55. 7. In a spring air gun, the combination with a frame having a segmental cylindrical portion and parallel spaced flanges depending therefrom, an air compression cylinder slideable in the segmental cylindrical portion of the frame, a piston in said cylinder, a

shank extending rearward from said piston, a spring on said shank, an abutment for the rear end of said spring slideable within said frame, a sear carried by said abutment, and a lever fulcrumed between the parallel flanges of said frame having a portion on one side of the fulcrum extending in rear of said spring abutment, a link connecting said portion to said abutment, a link connected to a portion of said lever forward of said fulcrum and extending to and connected with said air compression cylinder, and means for actuating said lever to move said cylinder and spring abutment simultaneously in opposite directions.

8. In a gun of the pump action type, the combination with a barrel, of a handle arranged adjacent to said barrel, and a flange extending inward from said handle through a slot in the barrel and having a segmental portion engaging the inner surface of the barrel.

9. In a gun of the pump action type, the combination with a barrel, of a handle adjacent to said barrel, a flange extending from said handle through a slot in the barrel and having a segmental portion for engaging the inner surface of the barrel, and a portion of said flange engaging the outer surface of the barrel.

10. In a gun of the pump action type, the combination with a barrel, of a handle adjacent to said barrel, a sheet metal member bent to form a core passing axially through said handle and having parallel flanges extending through a slot in said handle and a slot in the barrel, said flanges terminating in segmental portions engaging the inner surface of the barrel, and a bearing on said metal member engaging the outside surface of said barrel.

11. In a gun of the pump action type, the combination with a barrel, of a handle adjacent to said barrel and having a concave segment therein for fitting about a portion of the barrel, a metal member fashioned to form a core passing axially through said handle and beyond one end of the same, and also having a laterally extending portion passing through a slot in the handle and a slot in the barrel and terminating in a segmental portion fitting the inner surface of the barrel, a bearing on the end projecting portion of said member fitting the outer surface of the barrel, and a connection between said end projecting portion and the member to be actuated.

12. In a gun of the pump action type, the combination with a barrel, of a handle adjacent thereto, a member fashioned to form a core passing axially through said handle and having a laterally projecting portion passing through a slit in the handle and terminating in a laterally projecting segmental flange, said barrel being provided with

struck-up flanges extending parallel to the surface of the barrel and separated by a slot, said flanges engaging the segmental portion of the handle member, and a bearing on said handle member for engaging the outer surface of the barrel.

13. In a gun, the combination with a stock, of a metallic frame attached thereto having downwardly projecting parallel flanges, and a trigger guard of U-shaped form having one side thereof secured to said parallel flanges at the rear end thereof and the other side engaging a portion of said frame adjacent to the stock.

14. In a gun, the combination with a stock, of a metallic frame attached thereto and having downwardly extending parallel flanges, and a trigger guard secured to said

frame forming a closure for the rear end of said downwardly extending flanges and 20 extending therefrom rearward and upward to the stock.

15. In a gun, the combination with a stock, of a metallic frame having a hollow cylindrical portion with downwardly projecting parallel flanges and rearwardly extending flanges overlapping the stock, of a trigger guard having a portion secured to and forming a closure for the rear end of said parallel flanges, and a portion extending rearward and upward therefrom, the latter portion having notched engagement with the rearwardly extending flanges of the frame.

In testimony whereof I affix my signature.

CHARLES F. LEFEVER.
